DIVIDER CONSTRUCTION FOR GOLF CLUB BAG

Robert E. Thompson, Des Moines, Iowa, assignor to Des Moines Glove & Mfg. Company, Inc., Des Moines, Iowa, a corporation of Iowa

Application March 25, 1957, Serial No. 648,258

3 Claims. (Cl. 150—1.5)

The present invention relates to golf bags, and more particularly to golf bags of the type provided with a closable, flexible hood connected to the upper end of the bag and adapted to be positioned for enclosing the upper area of the golf clubs normally projecting out of the bag, for protecting the golf clubs during inclement weather, or during storage, or transportation of the bag and clubs. Usually, the hoods for golf bags are so designed that upon their being opened they may be folded down into the bag so as to lie in close proximity to the inner wall of the bag, thereby permitting convenient insertion of the clubs, and removal from the bag.

Heretofore, such golf bags were, in general, provided with dividers positioned in the mouth of the bag for segregating the golf clubs into desired groups. In some recent constructions of golf bags, the dividers were removably mounted in place by, and supported on, flexible straps, which have not been found satisfactory because the straps and dividers tend to sag and bow due to the weight of the clubs thereagainst, and which results in improper club segregation and division. Such constructions also tend to pull in the side walls of the bag, and thereby reducing and distorting the size and shape of the mouth of the bag, which further impairs its proper and efficient use.

In other constructions, dividers have been employed which permit their removal or securement in place in the mouth of the bag by screws or thumb screws inserted from the exterior of the bag. Such constructions have not been found totally satisfactory due to the difficulty and time consumed in placement and removal of the dividers, and because the screws frequently become lost in process of removal or replacement. Furthermore, thumb screws projecting externally of the bag also are objectionable because of their catching on and snagging against clothing and other objects.

One of the objects of the present invention is to provide a novel divider construction for golf bags which totally obviates the foregoing objections.

Another object is to provide a novel divider construction for golf bags which permits quick and easy removal of the divider from, and remounting in, the mouth of the bag. A further object is to provide a novel divider construction for a golf bag which may be quickly and easily removed from, and remounted in, the mouth of the bag, and which assists in maintaining the proper size and shape of the mouth of the bag and insures proper spacing and segregation of the clubs in the bag.

Still another object is to provide a novel divider construction for golf bags which is simple, efficient in use, and capable of being economically manufactured.

Other objects and advantages of this invention will be apparent from the following description, taken in connection with the accompanying drawing, in which:

Figure 1 is a side elevational view of a conventional golf bag with portions of the side wall broken away to show details of construction, it being provided with the novel divider construction embodying the present invention.

2

Figure 2 is a fragmentary view of the upper portion of the golf bag represented in Figure 1 of the drawing showing the closable, flexible hood extended in operative position.

Figure 3 is a top plan view of the upper end of the golf bag showing the novel divider construction.

Figure 4 is a vertical section through the upper portion of the bag taken substantially as indicated at line 4—4 on Figure 3.

Figure 5 is a sectional view of the divider construction taken as indicated at line 5—5 on Figure 3.

Figure 6 is an enlarged view, part in section and part in elevation, of one of the divider elements embodying the present invention.

Figure 7 is a fragmentary face view, taken as indicated at line 7—7 on Figure 4, showing one of the mounting brackets for the divider.

As represented in the drawing, the conventional golf bag is indicated generally at 10, having a pair of apparel pockets 12 and 14, and a handle 16. The bag is usually provided with a conventional shoulder strap, not shown. Generally, the body of the bag and its pockets are formed of flexible material, such as leather, canvas, and other fabrics. The upper end of the bag is usually provided with a rigid reinforcing member to define the mouth of the bag, and the side member is surrounded by a suitable covering material, such as leather, as indicated at 18, so as to protect the golf clubs that come in contact therewith.

Surrounding the upper portion of the bag is a relatively rigid reinforcing collar 20, of any suitable material, such as leather, fiber, or the like, to which is attached the body of the bag. Also secured to the side of the collar, directly or by attachment to the inner wall of the bag, is a closable, flexible hood 24 which, as shown, is provided with a relatively wide mouth opening adapted to be closed by a conventional zipper 26. When the zipper is moved to open the hood, the body of the hood may then be folded downwardly through the mouth into the interior of the bag so as to lie in close proximity to the inner surface of the wall of the bag, as seen in Figures 1 and 4 of the drawing.

When the hood is extended and closed, as seen in Figure 2, it serves to surround and fully enclose the upper ends of the projecting portions of golf clubs within the bag. Secured to one wall of the flexible hood is a suitable pocket, as indicated at 28, which is exposed for use when the hood is extended to operative position, as seen in Figure 2, and which pocket provides a convenient place of storage for the divider elements that have previously been removed from the mouth of the bag for the purpose of enabling the hood to be withdrawn to its extended position.

As illustrated in the drawing, the golf bag is provided with a pair of structures embodying the present invention. Due to the generally triangular shape of the mouth of the bag as represented, the divider structures are of different lengths, but otherwise are essentially the same in construction and operation. Each divider structure includes an elongated, preferably cylindrical supporting member 30, formed at one end with a rigid projection or trunnion 32. The opposite end of the supporting member is formed with an elongated bore or passage 34, in which is slidably mounted a rigid member 36 which, at its outer end, is formed with a reduced projection or trunnion 38. The member 36 is formed with a longitudinally extending slot 40, into which projects a screw 42 threaded through the wall of the bore of the supporting member 30.

A coil spring 44, is positioned within the bore 34, and seats against the inner end of the members 36, so as to yieldingly project the member 36 to its maximum limited position as determined by the set screw 42 abutting one end of the slot 40. By virtue of this construction, the member 36 with its projection 38 may be yieldingly moved

in and out with respect to the main support member 30.

Mounted in aligned relation on the opposite surface of the inner wall of the bag in registration with the collar 20, are a pair of bracket members 48, for each divider structure. The bracket members 48 are rigidly attached in place by rivets 50, extending through the reinforcing collar of the bag. These bracket members 48 are provided with a raised central circular portion 52, which is provided with a central opening 54, for the reception of the projections 32 and 38 of the divider. The divider may be quickly placed in operative position by first inserting the projection 38 into the opening 54 of one of the bracket members, and pressure is exerted longitudinally so that the adjacent shoulder of the projection 38, abuts against the embossed portion 52 of the bracket, and by virtue of the construction above described, the main support member 30 telescopes over the member 36 for shortening the overall length of the divider, until the projection 32 at the opposite end may be registered with the opening 54 of the opposite bracket member. Upon release of pressure, the spring 44 will then expand the assembly so that both projections 32 and 38 remain firmly seated in the respective brackets. To remove the divider assembly, the opposite procedure is followed.

The main supporting member 30 of the divider structure may be formed of any suitable material, and preferably each divider assembly is surrounded by and constitutes a support for a divider flap, indicated at 60. Preferably, though not necessarily, the divider flap is made of leather and is wrapped at its upper end around the member 30, and is secured in place by stitching. The divider flap assists in protecting the clubs within the bag, and in providing proper support for the clubs in a segregated manner. For convenience in use, the divider flaps at all times remain in assembled relation with the divider structure. When the dividers are removed from the mouth of the bag preparatory to extending the hood 24, to the position seen in Figure 2 of the drawing, said divider assemblies may be temporarily stored in the pocket 28 of the hood.

Although I have herein shown and described certain preferred embodiments of my invention, manifestly it is capable of further modification and rearrangement of the parts without departing from the spirit and scope thereof. For example, in lieu of the specific arrangement disclosed as yieldingly maintaining the divider assemblies in operative position, I might choose to employ a divider of rigid, unitary structure having a pair of fixed projections or trunnions at opposite ends, and wherein the spring means for maintaining the divider in operative position may be enclosed in a modified form of one of the bracket members. I do not, therefore, wish to be understood as limiting this invention to the precise embodiment herein illustrated, except as I may be so limited by the appended claims.

I claim:

1. In a golf bag having a flexible, closable hood attached to the upper end of the bag and adapted to be opened

and folded down into the bag in close relation to the inner wall of the bag; the improvement comprising one or more club dividers removably mounted and totally supported on the inner side walls of the mouth portion of the bag, 5 said divider including a pair of bracket members fixedly secured to opposite inner side walls of the upper end of the bag, an elongated support member having reduced shouldered projections at opposite ends for seating in said bracket members, and spring means associated with one of said members for releasably securing said projections in operative position in said bracket members, whereby upon removal of the dividers the hood may be withdrawn from the bag to an extended position for enclosing the upper ends of the golf clubs in the bag.

15 2. In a golf bag having a flexible, closable hood attached to the upper end of the bag and adapted to be opened and folded down into the bag in close relation to the inner wall of the bag; the improvement comprising one or more club dividers removably mounted and totally supported on the inner side walls of the mouth portion of the bag, said divider including a pair of bracket members fixedly secured to opposite inner side walls of the upper end of the bag, an elongated support member having reduced shouldered projections at opposite ends for seating in said bracket members, one of said projections being mounted for longitudinal movement relative to said supporting member, means for limiting said movement in an outward direction, and spring means carried by said supporting member for yieldingly urging said one projection to its outer limited position of movement.

20 3. In a golf bag having a flexible closable hood attached to the upper end of the bag and adapted to be opened and folded down into the bag in close relation to the inner wall of the bag; the improvement comprising one or more club dividers removably mounted and totally supported on the inner side walls of the mouth portion of the bag, said divider including a pair of bracket members fixedly secured to opposite inner side walls of the upper end of the bag, an elongated support member having reduced shouldered projections at opposite ends for seating in said bracket members, one of said projections being mounted for longitudinal movement relative to said supporting member, means for limiting said movement in an outward direction, and spring means carried by said supporting member for yieldingly urging said one projection to its outer limited position of movement.
